(57) **CLAIM**

The ornamental design for a table, as shown and described.

DESCRIPTION

FIG. 1 is a perspective view of a table comprising the new design;

FIG. 2 is a top view thereof;

FIG. 3 is a front view thereof;

FIG. 4 is a right side view thereof; and,

FIG. 5 is a front view of an alternative embodiment of the table, having an indeterminate width, which is the sole difference between it and FIGS. 1-4.

The broken line depiction is for illustrative purposes only and forms no part of the claimed invention.

1 Claim, 5 Drawing Sheets

FIG. 1

FIG. 2

FIG. 3

FIG. 4
